VARIABLE IMPULSE TRANSMITTER

Charles C. Smith, Adrian, Mich., assignor to
Faraday Electric Corporation, Adrian, Mich., a
corporation of Michigan

Application February 25, 1946, Serial No. 650,059

3 Claims. (Cl. 177—380)

1

This invention relates to a control station of compact and simple form, which is readily portable and which has a wide range in its selectable designations.

This invention has utility when incorporated in an electrically connected desk unit, as a switch selector and control in a variable impulse transmitter for remote devices selectively placed in circuit therewith. More especially, the disclosure is a signal means in code calling. The signal transmitted may be evidenced by visible means, as flashes of light, or by sounds, as buzzers, bells, horns, chimes and the like. In the embodiment, the signals may be construed as somewhat analogous to telegraphic code signaling.

Referring to the drawings:

Fig. I is a plan view, with portions broken away, of an embodiment of the invention as a code-signalling unit of small dimension, which may be located on a desk, and which unit is operable to select and transmit signals;

Fig. II is an enlarged view, from the left of Fig. I, with some parts broken away, and showing the control switch;

Fig. III is a view from the right, or opposite end of the unit from the showing in Fig. II, having the motor drive and transmission shown fragmentarily;

Fig. IV is a developed or flat view of the wrap section forming the drum for the selective switch control and located medially of the unit in Fig. I;

Fig. V is a front view of the signal switch, parts being broken away;

Fig. VI is a wiring diagram of the electric circuits for the motor and signals;

Fig. VII is a side elevation, from the front of the unit, showing the barrel or cam drum, with the inner or switch control ported drum at its limit of throw to the right;

Fig. VIII is a partial view on the line VIII—VIII, Fig. VII, showing the control disk end for the barrel at "off" position;

Fig. IX is a partial view on the line IX—IX, Fig. VII, showing the selector disk end of the barrel, also at "off" position as released by the control disk;

Fig. X is a side elevation, from the front of the unit, showing the barrel or cam drum with the inner or switch control ported drum at its limit of throw to the left, or most remote from the showing in Fig. VII;

Fig. XI is a view on the line XI—XI, Fig. X, showing the control disk end for the barrel at "on" position;

Fig. XII is a view on the line XII—XII, Fig. X,

showing the selector disk end of the barrel, also at "on" or locked position as determined by the control disk;

Fig. XIII is a section thru the barrel on the line XIII—XIII, Fig. XI, showing the outer drum in section and the inner drum in elevation; and

Fig. XIV is a fragmentary view from the left of Fig. X, showing the "on" position of the switch as closed.

The housing

Screws 1 thru suction cups 2 (Figs. II, III, V) and the corners of a base plate 3, assemble end caps or housing members 4, 5 (Figs. I, II, III, V) with the base plate 3. A pin 6, thru a spring tongue 7, may pull, from remote flange end 8 having engagement with the forward under side of the plate 3, a major medial housing section 9, into position to overlap the respective end housing members 4, 5.

Parallel arc slots 10, 11 (Fig. I), have teeth 13 protruding therethru. These teeth 13 at the right and protruding thru the slot 10 are on a selective disk member 14, while the teeth 13 at the left are on a control disk member 15. The housing wrap or shield 9 is between the slots 10, 11, and has a port or window 16 to expose a selected call, as disclosed thru the window upon rotating the member 14. In line with the window 16, is a shorter window or port 17 for disclosing "off" indicator 18 (Figs. V, VII, X). Upon rotation of the control member 15, effected by the operator thru shifting the teeth 13, the "off" indicator 18 is brought to register with the port 17. At this position the unit is idle. Furthermore, the member 14 is released, to permit manual selection or re-selection by the operator pushing or pulling the teeth at the right for movement along the slot 10. For starting the unit, the teeth 13 at the control member 15 are shifted along the slot 11 to bring an "on" indicator 19 into register with the port 17.

The motor drive

An insulated flexible conduit 20 has therein electric current power supply lines 21, 22 (Figs. I, VI). An instance herein taken is for a commercial supply current of sixty cycle one hundred ten volt alternating current. The lines 21, 22, enter the unit thru an insulation grommet 23 in the housing 4. The line 21 extends directly to a synchronous motor 24 at the right (Fig. I). The line 22 is to a switch terminal or contact 25, normally open or clear of a contact 26 (Fig. II).

From the contact 26 there is a connection thru a line 27 to a second switch 25, 26 (Figs. II, VI, XIV). With these switches closed, the motor 24 (Figs. I, VI) is connected to operate.

The selector indicator

A rim or flange 28 on the member 14 is slightly inward from the teeth 13. The rim 28 has an end lug 29 to receive an inturned end 30 (Figs. II, 10 VIII) of a transparency 31 (Figs. I, V) to be wrapped over a call identifying sheet 32. The sheet 32 has thereon code number designations 33 with persons or stations 34. Remote from the end 30, the sheet 31 has a similar snap-in mounting for its other end. The sheet 31 is thus in position to hold the sheet 32 in position for travel within the housing 9 past the window 16.

Setting means for the selector switch

An outer drum or barrel 35 (Figs. V, VII, X) is fixed with the selector member 14. The opposite end of the drum 35 has an outward return flange 36. The inner sides of the mountings for the indicators 18, 19, coat as an outer bearing seat 37 fixed with the member 15, in which seat 37 the flange 36 rides.

A radial arm 38 (Figs. V, IX, XII) inward from the member 14 provides centering means for the drum 35 in its mounting on a shaft 39. The shaft 39 is mounted in bearing brackets 40, 41, rising from the base 3 (Figs. V, VII).

The drum 35 has a helical slot or cam way 42 thru which extends a knob or head 43, slidably mounted on a rod 44 (Figs. II, V, VII, X, XIII) terminally fixed in the brackets 40, 41. This mounting fixes the rod 44 in parallel with the shaft 39. Movable with the head 43 as directed by the way 42 for shifting lengthwise of the drum 35, is a U-shaped spanner 45. The head 43 engages the medial or cross-over portion of the spanner 45, while the legs therefrom extend toward the shaft 39 to have therebetween an inner drum 46. The drum 46 of the indexing means, is freely slideable along the shaft 39, but is held from rotation relatively to the shaft 39 by a spline 47.

A locking tongue 48 enters corner end notches 49 of an indexing plate 50 (Fig. IV) in holding this plate as the cylindrical face for the inner drum 46. The ends of this plate 50, when formed into the drum 46, are slightly spaced to provide a slot 51 (Figs. V, XIII) extending lengthwise of the drum 46. At the normal stop position for the drum 46, a downward pointed finger 52 is in approximate register to enter the slot 51.

The finger 52 is at the free end of a switch contact arm 53. There is normal downward flexing tendency for the arm 53 toward a companion contact 54. While the pointer finger 52 may enter the narrow slot 51, the finger 52 must come to a more wide opening in the drum 46 to allow the contacts 53, 54 to close a circuit.

A signal circuit supply line 55 (Figs. I, V, VI) is to the switch 53, 54. A lead 56 extends from the switch 53, 54, to a series of remote signal means 57, the circuits from which are completed by a line 58. The opening and closing of the switch 53, 54, is effected thru the rotation of the drum 46. The rotation of the drum 46 is not from the direct rotation of the disk 14, which only shifts the drum 46 axially, nor from the turning of the disk 15. However this latter disk 15 is effective indirectly, for it cuts in the motor

24 which has a speed reduction transmission gearing 59 to drive the shaft 39.

Control switch setting and interlock

- 5 The control disk 15 is free for turning relatively to the rod 44 extending therethru, for the rod 44 as fixed by the brackets 40, 41, has clearance by a slot 60 in the disk 15 (Figs. II, VIII, XI). At counterclockwise limit of throw, looking from the barrel or drum side of the disk 15, the rod 44 is at the lower end of the slot 60 as a stop, and the control identification "off" is at the window 17. There is a snap-throw of the control member 15 to this position effected thru 15 a radial arm 61 fixed with the member 15 which is loose on the shaft 39. The free end of the arm 61 (Figs. II, V, XIV) has a grooved knob 62 for a wrap portion of an arced wire spring 63 rising from its anchor 64 in the base 3. In this limit 20 of throw for the member 15 into the end of the slot 60, the flexed spring 63 passes a maximum flex or intermediate dead point and snaps the member 15 to expose the "off" indication 18 at the window 17.
- 25 At this "off" position for the member 15, a cam portion 65 (Fig. II) of the arm 61 allows the flexible strip carrier for the switch contact 25 to move away from the contact 26 for this switch to be open. Lying against the free end of the 30 strip carrying the contact 25 and on the side thereof toward the contact 26 is an arm 66 fixed on a rock shaft 67 mounted in the brackets 40, 41, parallel to the shaft 39, and opposite from the rod 44.
- 35 Fixed on the shaft 67 adjacent the member 14 is a pawl or stop carrying arm 68 (Figs. II, IX, XIII). At all contact or closed positions for the switch 25, 26, the strip carrying the contact 25, lifts the arm 66 sufficiently to hold the free end 40 of the arm 68 in engaging relation with the teeth 13 of the member 14. However, as the control 50 member 15 be rotated to "off" position, and there be freedom for the switch 25, 26, to open, then the shaft 67 is rocked to swing the arm 68 clear of the disk 14. The disk 14 is thus released.
- 55 A window 69 (Figs. II, VIII, XI) in the member 15, just away from the control slot 60, provides ample clearance for the mounting strips carrying the switch contacts 53, 54. These strips 50 in their extent from inside the drum 35 thru the disk 15 are to an insulation block 70 at an inwardly offset top of the bracket 41. The arms 61, 66, are also of insulation material.
- 60 Fixed with the shaft 39 is an insulation disk 65 or cam 71 having a notch 72. This notch 72 is so angularly positioned as to the narrow slot 51 on the inner drum 46 that, as the flexible strip carrying the contact 25 rides into the cam notch 72, the pointer 52 (Figs. III, V, XIV) is at the slot 51. This insures that no "off" throwing of the control member 15 is effective until the rotation of the inner drum be completed by the pointer 52 being in register with the slot 51. In practice this means there may be no interruption whatsoever of any call to break into a fraction or incomplete call signal.
- 65 The interlock arises from throwing of the control member 15 to bring "on" 19 to the window 17. This rocking of the member 15 is reversely past the radial maximum flex region for the spring 63 and snaps the member 15 to have the rod 44 ride in the opposite or upper end of the slot 60. This swings the arm 61 (Fig. II) so that its cam 65 acts upon the flexible strip 70 mounting the contact 25 to shift it clear of the

notch 72, should it be therein. If the strip already has the contact riding on the disk 71 away from the notch 72, then this shifting of the member 15 to "on" position precludes re-entrance to the notch 72. It is accordingly seen that an interlock relation is established beyond that for "off" as a sequence ending stop only, but for "on" to be effective at starting or curing a signaling performance. At all occasions to shift to "on" indication 19 to be exposed at the port 17, there is such positioning of the arms 61, 66, 68, that the selection member 14 is locked. Power current may now be effective thru the motor 24 and the transmission 59 to cause the inner drum 41 to rotate slowly and continue so to do so long as "on" be the designation at the window 17.

In order to cause change of designation at the window 16, the operator may use his fingers to engage the exposed teeth 13 of the selector member 14. However, so long as "on" is at the window 17, the selection may not be made. The operator must first shift the disk 15 to bring "off" to the window 17. The turning of the member 14 moves therewith the drum 35 and the sheets 31, 32. The drum 46 is turned as driven by the motor 24.

Indexing for call identifications

At the limit counterclockwise throwing or turning of the selector member 14, looking from the right of Fig. V, the head 43 is at the end of the helix guide 42 toward the member 14. Taking this as an initial or starting position, in order to get thereto, at the port 17, there must be showing of the "off" designation 18.

The plate 50 which is wrapped to form the drum 46 is provided with selector openings. The drum 46 is now in its closest position to the member 14. Opening 73 (Fig. IV) is the nearest thereto, and there may be adopted "1" to be exposed at the window 16, and with alphabetical listing, this may be F L Andrews. At each rotation of the drum 46, the pointer 52 rides once into the opening 73 for a single short electric signal to be sent. At a next position over for "2" to show at the window 16, say for D C Barker, the pointer 52 makes two quick contacts in close succession with a gap. In addition to the opening 73, the contact device 52 rides into an opening 74. For three, four and five contacts, additional openings 75, 76, 77, are in the drum 46.

In order to effect the change from "1" to "2," it is necessary to shift the disk 15 from "on" to "off." Then when the pointer 52 rides in the slot 51, the pawl 68 is released and the disk 14 may now be moved to "2." The operator then turns the disk 15 from "off" to "on" and the two quick flashes or sounds are transmitted to the remote signals spaced by a considerable gap.

At this "on" position, it may be considered that the motor 24 has its speed reduction therefrom impart to the shaft 39 a speed in the range of 7 R. P. M. The provision of about 8½ seconds for each revolution permits a readily noticeable gap between as many as ten contacts as quickly made during one revolution of the shaft 39. This gap determines the space or clearance between the succession of signals. Further identification aid is provided in holding the spacings between the openings 73, 74, 75, 76, 77, rather close, and a wider gap to an opening 78, with its succession of shorter openings 79, 80, 81, 82. The cycles continue unless some time interval or limit be provided or there be throwing to "off" to open the

switches 25, 26, 53, 54. The chart or index 50 (Fig. IV) is adaptable to handle 30 calls:

5	1—opening	73
5	2—	73, 74
	3—	73, 74, 75
	4—	73, 74, 75, 76
	5—	73, 74, 75, 76, 77
10	11—	78, 73
10	12—	78, 73, 74
	13—	78, 73, 74, 75
	14—	78, 73, 74, 75, 76
	15—	78, 73, 74, 75, 76, 77
	21—	79, 78, 73
	22—	79, 78, 73, 74
15	23—	79, 78, 73, 74, 75
	24—	79, 78, 73, 74, 75, 76
	25—	79, 78, 73, 74, 75, 76, 77
	31—	80, 79, 78, 73
	32—	80, 79, 78, 73, 74
20	33—	80, 79, 78, 73, 74, 75
	34—	80, 79, 78, 73, 74, 75, 76
	35—	80, 79, 78, 73, 74, 75, 76, 77
	41—	81, 80, 79, 78, 73
	42—	81, 80, 79, 78, 73, 74
25	43—	81, 80, 79, 78, 73, 74, 75
	44—	81, 80, 79, 78, 73, 74, 75, 76
	45—	81, 80, 79, 78, 73, 74, 75, 76, 77
	51—	82, 81, 80, 79, 78, 73
30	52—	82, 81, 80, 79, 78, 73, 74
	53—	82, 81, 80, 79, 78, 73, 74, 75
	54—	82, 81, 80, 79, 78, 73, 74, 75, 76
	55—	82, 81, 80, 79, 78, 73, 74, 75, 76, 77

It is to be noted that the openings 74, 75, 76, 77, as crosswise of the chart 50, extend lengthwise of the drum 46. The interruptions in the respective rows register with the commencement of the continuous openings 78, 79, 80, 81, 82, in their extent lengthwise of the drum 46, as from the right (Fig. IV). That is, the first signal after the first opening 74, is for the openings 73, 78, with the gap greater than the 73, 74, two contact signal per cycle. With the control at "off," the selector 14 may be operated to any desired first selection, as "54." As the call has been given, a desired interval, the control may be again shifted to "off," another selection made as "31" or "15," and the control member 15 again set for "on" to have the signal sent out. One or more calls are completed before re-selection may be made, notwithstanding disk 15 be set to "off."

In the embodiment operating acceptably hereunder, the motor 24 is of the self-starting synchronous type. A small space unit may be with 55 a governed series type motor, or even of other types of appropriate dimensions.

While reference to the speed reduction of the motor 24 is suggested to be in the range of 7 R.P.M., even with such a predetermined speed, 60 the intermediate gearing 59 may establish a still more slow rate. Also the motor speed may not require such a slow down and still leave the signals readily distinguishable. The detectable gap at "55" is from the openings 82—87. The motor 65 itself may take care of the slow down speed sought, even with the absence of the gearing 59.

The character of the terminals is for safe electric current to be thru the unit and adequate for a signal circuit. In practice, 5 ampere current at 70 115 volts has been used acceptably. However, a preferred range is not to exceed 5 ampere and the voltage not over 50. When there is a range of voltage above 50, say even up to 115 volts, 1 ampere signal current is more desirable for main- 75 tained performance.

What is claimed and it is desired to secure by Letters Patent is:

1. A diverse communication transmitting unit comprising an index drum, a motor, a transmission from the motor including a shaft coaxial with the drum and keyed thereto for relative axial shifting, a manually rotatable selector drum coaxial with and exterior of the index drum, a control coacting with the selector drum for determining a lock position for the index drum against rotation, connection means between the drums responding to selector drum axially positioning the index drum as to said shaft while the index drum is held against rotation, and interconnecting means from the control as shifted to unlock the drum for cutting in the motor to rotate the drum.

2. A code-calling portable unit comprising a base, brackets thereon, a rotatable shaft in the brackets, a slow speed motor drive for the shaft, an index drum splined to slide along the shaft between the brackets, a manually rockable selector exterior of the index drum concentric of and movable relatively to the shaft in its extent from one bracket toward the other, a limited rock control aligned with the selector, a switch for cutting in the drive, connecting means from the control "off" position to open the drive switch and including release means for the selector, an index drum responsive switch, and connecting means from the control "on" position to set the release means to hold the selector and including,

15

20

30

at code starting position for the index drum, a drive switch closing for the index drum to rotate and operate its switch.

3. A unit comprising a housing, bearing means in the housing, a shaft rotatable in the bearing means, an index drum mounted on and connected to rotate with the shaft, a rotatable selector mounted on the shaft and having connection to move the drum relatively to the shaft, and a rockable controller also mounted on the shaft and movable relatively to the shaft and having engaging means operable therefrom to lock and release the selector.
